R. O. TAYLOR.

WINDOW FOR VEHICLE CURTAINS.
APPLICATION FILED MAY 10, 1920.

1,380,606.

Patented June 7, 1921.

UNITED STATES PATENT OFFICE.

RITCHIE O. TAYLOR, OF DETROIT, MICHIGAN, ASSIGNOR OF ONE-HALF TO JACK HEINZE, OF DETROIT, MICHIGAN.

WINDOW FOR VEHICLE-CURTAINS.

1,380,606.

Specification of Letters Patent. Patented June 7, 1921.

Application filed May 10, 1920. Serial No. 380,069.

To all whom it may concern:

Be it known that I, RITCHIE O. TAYLOR, a citizen of the United States, residing at Detroit, in the county of Wayne and State 5 of Michigan, have invented a new and useful Window for Vehicle-Curtains, of which the following is a specification.

This invention relates to windows for vehicle curtains and more particularly for the 10 curtains of automobiles.

It is the object of the invention to provide a vehicle curtain window comprising a frame adapted to be clamped to the curtain, marginally to the window opening 15 therein, and providing a seat for the glass or like transparent member, and to provide means for securing the glass in said frame, independent of the means attaching the frame to the curtain.

20 With this object in view, the invention consists in the construction and arrangement of parts hereinafter described and illustrated in the accompanying drawing, wherein,

25 Figure 1 is an interior view of the window, with the glass retaining ring removed.

Fig. 2 is a view of the inner side of a portion of said retaining ring.

30 Fig. 3 is a cross-section view taken on line 3—3 of Fig. 1, showing in detail the means clamping the frame for the glass to the curtain, and for retaining the glass in said frame.

35 In these views the reference character 1 designates a vehicle curtain having a circular window opening, and 2 is a circular metallic frame or ring which is exteriorly secured to said curtain, marginally of said 40 opening. The curtain engages the inner face of said ring (see Fig. 3) and is clamped into a shallow annular channel or groove 3 in said face by a sheet metal ring 4, the edges of which force the engaged portions 45 of the curtain into deepened marginal portions 5 of the groove 3. Between said edges the ring 4 is bowed out from the ring 2 and is secured to the latter by a plurality of tap screws 6. To adapt the clamping ring 4 to more firmly engage the curtain 1, the edges of said ring are scalloped as is clearly shown in Fig. 1. An inwardly projecting flange 7 on the frame 2 provides a seat for the glass or other transparent member 8; the 55 portion of the curtain peripheral to the

window opening being engaged between the edge of the glass and the frame 2, as indicated at 9, and further extended between the glass 8 and its seat 7 as shown at 10. To retain the glass in its frame there is 60 employed an inner ring 11 curved in cross section to clear the bowed ring 4, and secured in place by a plurality of tap screws 12 which pass freely through suitably located openings 13 in the ring 4 and engage 65 the frame 2. The inner ring 11 bears upon the frame 2 at each side of the groove 3, clamping the portions of the curtain which engage beneath it, and projects inwardly 70 beyond the edge of the glass 8 sufficiently 75 to retain the latter securely in place.

From the preceding description it will be seen that the ring 11 and screws 12 form a means for holding the glass in its frame quite independently of the ring 4 and 80 screws 6 which are depended upon to secure the frame 2 to the curtain. Thus in case occasion arises to replace the glass this may be easily and expeditiously accomplished without disturbing the mounting of 85 the window frame upon the curtain. In addition to holding the glass in place, however, the outer ring 11 supplements the ring 4 in clamping the frame to the curtain and also prevents the screws 6 from working 90 free of the frame as a result of vibration. The exposed faces of the frame 2 and ring 11 may be nickel-plated or otherwise treated to impart a finished and ornamental appearance to the device.

It will be apparent that by the above described means for securing the frame to the curtain independent of the glass or transparency, the handling of the curtain in manufacture and hanging is facilitated, 95 that breakage of the transparency in such handling is avoided, that the assembly of the glass within the frame or the removal or renewal thereof may be quickly and conveniently accomplished without disturbing 100 the fixed relation of the frame and curtain, and that the parts when finally assembled will be firmly held against slippage or displacement through vibration, thus insuring 105 a substantially permanent and water-tight joint between the engaged parts.

What I claim is:

1. In a window for vehicle curtains, the combination with a curtain having a window opening, of a transparent closure for said 110

opening, a frame providing a seat for said closure, a clamping member securing said frame to the curtain, and a retaining member for said closure covering the clamping member and secured independently of the latter to said frame.

2. In a window for vehicle curtains, the combination with a curtain having a window opening, of a transparent closure for said opening, a frame providing a seat for said closure, a clamping member securing said frame to the curtain, and a retaining member for said closure covering the clamping member and secured independently of the latter to said frame, a portion of the curtain being engaged between said closure and its seat upon said frame.

3. In a window for vehicle curtains, the combination with a curtain having a window opening, of a transparent closure for said opening, a frame providing a seat for said closure, a clamping member between which and said frame a portion of the curtain marginal to said opening is engaged, means securing said clamping member to the frame, a retaining member for said closure covering said clamping member, and members securing said retaining member to the frame, passing freely through the clamping member.

4. In a window for vehicle curtains, the combination with a curtain having a window opening, of a transparent closure for said opening, a frame providing a seat for said closure, said frame having a groove co-extensive therewith, a clamping member detachably secured to said frame within said groove, between which member and said

frame a portion of the curtain marginal to said opening is embraced, and a retaining member for said closure covering said clamping member and detachably secured to the frame independently of said clamping member.

5. In a window for vehicle curtains, the combination with a curtain having a window opening, of a transparent closure for said opening, a frame providing a seat for said closure, said frame having a groove co-extensive therewith, a clamping member detachably secured to said frame within said groove, between which member and said frame a portion of the curtain marginal to said opening is embraced, the edges of said member being scalloped to more securely engage the curtain, and a retaining member for said closure covering said clamping member and detachably secured to the frame independently of said clamping member.

6. In a window for vehicle curtains, the combination with a curtain having a window opening, of a transparent closure for said opening, a frame providing a seat for said closure, said frame having a groove co-extensive therewith having marginally deepened portions, a clamping member detachably secured to said frame within said groove and having scalloped edges engaging the curtain in the deepened portions of said groove, and a retaining member for the closure detachably secured to the frame independently of said clamping member.

In testimony whereof I sign this specification.

RITCHIE O. TAYLOR.
